UNITED STATES PATENT OFFICE.

EDWIN PALMER LEE, OF CARDIFF, ENGLAND.

KILN FOR BURNING CLAY GOODS.

SPECIFICATION forming part of Letters Patent No. 593,723, dated November 16, 1897.

Application filed March 11, 1896. Serial No. 582,703. (No model.) Patented in England December 1, 1892, No. 21,945.

To all whom it may concern:

Be it known that I, EDWIN PALMER LEE, a subject of the Queen of Great Britain and Ireland, residing at Cardiff, Glamorgan county, England, have invented certain new and useful Improvements in Kilns for Burning Clay Goods, also for Burning Sanitary Ware and for Salt Glazing, (which has been patented to me in Great Britain under date of December 1, 1892, No. 21,945,) of which the following is a specification.

The invention applies to all that class of kilns in which fuel is economized by using the partially-cooled products of combustion from the first kiln in another kiln in which the preliminary warming has been commenced and is nearly ready for burning and leading the products of combustion from the second kiln to another containing greener goods, and so on. I have devised a peculiar arrangement of flues provided with controlling-dampers connecting a series of kilns with each other and with the stack.

My improvement allows a correspondingly graduated cooling of the several kilns when the burning is complete, receiving the fresh cold air into a kiln which is nearly cooled, discharging the partially-warmed air into another kiln in which the cooling has made less progress, and discharging the hotter air therefrom into the least cool one in which the firing has but just been completed. My invention attains great perfection in the combustion by utilizing the fresh air heated by the cooling of the goods, so that it will on mingling with the gases induce the complete combustion of any unburned material which may remain therein. In burning the contents of each kiln the hot gases are delivered to each kiln below the perforated bottom thereof. After ascending through the green goods and drying the same the hot gases are drawn off to act similarly in another kiln containing greener goods, and so on throughout as many kilns as the heat retained will profitably allow. I conduct the heat given off from the goods in cooling to the back of the furnace of a kiln in which goods are in process of burning and thus obtain very perfect combustion and economy in fuel.

In the accompanying drawings, Figure 1 represents a sectional plan on the line *y y* of

Fig. 2 of a rectangular kiln constructed and provided with flues and dampers in accordance with this invention. Fig. 2 represents 55 a vertical section on the line *x x* in Fig. 1. Fig. 3 shows a series of such kilns. In this latter figure the flues are indicated by dotted lines. At Fig. 4 of the drawings is represented a sectional plan of a circular kiln constructed and fitted with flues in accordance 60 with this invention. Fig. 5 is a corresponding vertical section on the line *y y* in Fig. 4, and Fig. 6 is a general plan of a series of such flues.

Similar letters of reference indicate corresponding parts in all the figures where they appear.

I will describe generally the mode of working with reference to Fig. 3 of the drawings for 70 a general plan and Figs. 1 and 2 for details.

From the flue *a*, which connects the kilns with the stack, are carried branch flues *b*, which communicate with the main or trunk flue *c*, connecting all the kilns in a series. 75 From the flue *c* branch flues *d* are carried into the kilns communicating with the perforated bottom, which is of an ordinary type. Opening into the top of the flues *e* are apertures *f*, Figs. 1 and 2, which are provided for acting 80 in an upward direction to supply hot air from a kiln behind to the back of the furnaces of the kiln being fired and for acting at another period in a downward direction to extract the steam or hot air from a kiln which is being 85 dried off by the hot draft proceeding from a burning kiln behind. Apertures *g* constitute 90 passages for communication between the flue *c* and flues *e*. The branch flues *d* are controlled by dampers *h* and *k*, and the flues *b* are controlled by dampers *m*. The main or 95 trunk flue *c* is controlled by dampers *j* and *l*. The flue *a* is controlled by dampers *n*. It may for convenience be assumed that the goods contained in kiln No. 1 have been duly burned 100 and require to be cooled. Instead of admitting cold air directly for this purpose and thereby risking injury to the goods the air may be drawn from, say, No. 6, in which the goods have been in process of cooling for some time. The air from No. 6 is drawn warm into No. 1 through the flues *c* and *b*, and the cooling of the goods in No. 1 is effected gradually.

Assuming the goods contained in kiln No. 2 to be in process of burning, the heat from kiln No. 1 is drawn through the flues *d* of kiln No. 1 into the main flue *c* and passes 5 thence into the flues *e* of kiln No. 2, whence it is discharged through the apertures *f* behind the bridges of the furnaces, and encountering the flame therein insures more complete combustion, thus effecting economy in fuel. The heat produced during the process 10 of burning the contents of kiln No. 2 is then conducted to kiln No. 3, the fire-holes of which are made air-tight by suitable covers, and by opening the dampers *h*, *k*, and *l* is directed 15 upward through the perforated floor of the kiln and the goods contained therein. The moisture extracted from the goods passes behind the screens or bag-walls *s* and is carried downward through the apertures *f* into the 20 flues *e* and through apertures *g* into the main flues *c* and thence into the stack *o* through flues *b* and *a*. The position of the stack *o* may vary according to convenience. When 25 the moisture has been removed from kiln No. 3, the process may be repeated in a similar manner with respect to kilns Nos. 4 and 5 by closing as many of the dampers *m* as may be necessary.

In the rectangular kilns dampers *q* are provided to enable any kiln to be shut out of the 30 series when desired. At such times the dampers *q* are closed over the openings *g*, leading into the flues *e*, and the dampers *j* and *l* being raised an uninterrupted passage is af- 35 forded for the heat through the main flue *c* underneath the kiln without leakage or counterdraft through the openings *g*, which would occur unless the said openings were closed by the dampers *q*. Access to the dampers *q* 40 is afforded through suitable holes at *p*.

The system of flues may be extended to kilns Nos. 7 and 8 without interfering with the working of the other kilns of the series.

The method of working with circular kilns and the flues and dampers therein, as shown 45 in Figs. 4, 5, 6, and 7, is substantially the same as that hereinbefore described with reference to rectangular kilns, except that the flues *e* existing in the latter case are dispensed with in the former and the apertures 50 *f* are made in the flues *d*.

The system of flues and dampers may be applied to other shaped kilns besides those shown in the drawings.

I claim as my invention—

The combination with a series of kilns, arranged in parallel groups and having the bag-walls *s*, of the stack, the main flue *a* delivering to the same, and extending between and connecting with the kilns of both groups 60 through damper-controlled branch flues *b*, *b*, dampers *m*, *m*, for the latter and dampers *n*, *n*, for the main flue, together with traversing flues *c*, *d*, *d*, arranged as shown and having direct and independently-controlled damper 65 communication at both sides of the kiln with the stack, the flues *c*, *d*, *d*, communicating through the bottom of the kiln with the interior thereof, the arrangement being such that fluid circulation may be reversed from 70 the rear of the bag-walls through the bottom and any kiln of either group may be placed in direct communication with one or more kilns of its own or of the other group, to supply or be supplied with heated air or gases, 75 substantially as herein specified.

EDWIN PALMER LEE.
